KEYBOARD CLUTCH

George W. Lawrence, Los Angeles, Calif., assignor
to William J. Pearson, Los Angeles, Calif.

Application October 23, 1931, Serial No. 570,623

3 Claims. (Cl. 192—28)

This invention relates to a keyboard clutch mechanism designed to be used in conjunction with a parcel post machine, such as is disclosed in the co-pending application Serial Number 367,106, filed May 29, 1929, by William J. Pearson, and entitled Parcel post weighing and stamp printing machine, which is designed to weight parcel post packages and to print parcel post stamps of the prepaid metered type.

10 The Parcel post weighing and stamp printing machine just referred to is designed for the printing of metered parcel post stamps, and, generally speaking, comprises weighing mechanism, printing mechanism, registering mechanism, and means for setting up on the printing mechanism the mechanical equivalent of a number or set of numbers set up by actuation of the keys of the keyboard.

15 An object of my invention is to provide a keyboard of the simplest form and character to provide ease and simplicity of operation for an operator of an otherwise complicated machine, and to provide a mechanism that will respond to a very light touch upon the keys of the keyboard; to that end, I have provided a series of power driven clutches disposed between the keys and the machine actuating elements; so that each key is in effect a clutch actuating element controlling the connecting of power to the machine operating elements.

An object of my invention is to provide a clutch connection between the keys and the power driven elements which is simple in construction, durable, instantly operable at the touch of a key and capable of transmitting the required amount of power to perform the work. This clutch construction is particularly designed for use in a machine such as the parcel post weighing and stamp printing machine referred to, wherein one revolution of the driving element actuates the connected mechanisms the required amount; and wherein there is a power return of the keys after their depression and before the completion of the rotation of the clutch, thus presenting the clutch releasing element in the path of the clutch for the clutch releasing operation, returning the keys to original position, and providing for only one clutch operation from one depression of a key.

To the above and other objects as may hereinafter appear, my invention consists in the novel construction, arrangement, and combination of parts as hereinafter fully, clearly, and concisely described and definitely pointed out in

my claims, and illustrated by the accompanying drawings, in which:

Fig. 1 is a front elevational view of an automatic keyboard, partly in section.

Fig. 2 is a sectional view in elevation from the right of the keyboard, showing one clutch in disengaged position.

Fig. 3 is a detail of the mechanism shown in Fig. 2, showing the clutch engaged and the trip disengaged by depression of a key.

Fig. 4 is a detail similar to Fig. 3, showing the driving element and the clutch after having made one-half of a revolution, with the key returned and the trip positioned to release the clutch.

Fig. 5 is a view similar to Fig. 4, but taken from the opposite side of the device.

Fig. 1 illustrates a keyboard designed to be used in a parcel post machine wherein a plurality of keys operate a corresponding number of clutches to engage and transmit power from a power source (not shown) to do work required in the machine. There is a supporting base 10, which may be part of the parcel post machine, upon which the keyboard unit is mounted by means of the frame 11; the frame includes an upper plate 12 through which pass the keys 13 and a control key 14 which operates the power clutch (not shown); a portion of the casing 15 for enclosing the machine is shown in Fig. 2.

For the purpose of description, the clutches will be treated in the singular, and the description will read as describing one clutch and its component parts only.

The drive shaft 16, which is here related by means of gears 17 and 18 to a source of power (not shown), rotates continuously and has keyed to it the ratchet wheel 19 which also rotates continuously, and provides, by means of its teeth, an engaging element whereby the clutch may be instantly contacted for the purpose of transmitting power with the least amount of lost time or motion.

Upon depression of one of the keys 13, the key bar 20 moves from the original position shown in Fig. 2 to the position shown in Fig. 3, the trip lever 21 is rocked on the shaft 22 on which it is mounted and thereby raises the end of the lever constituting the trip 23; this allows the latch 24, under tension of spring 25, to rock in one direction. Latch 24 is rockably mounted on pin 26 in cam 28. The rocking of the latch 24 by spring 25 brings the tooth 27 into the path of one of the teeth on the ratchet wheel 19, which constitutes the operation of engaging the clutch. The cam member 28 is rotatably mount-

ed on shaft 16, and bears on one side the pin 26 and the stop pin 29, which engages the latch 24 by means of the elongated opening 30. The latch 24 also has secured to it one end of the spring 25. On its other side cam 28 is provided with an eccentric 32. This eccentric carries and operates an eccentric ring 31, which is provided with an extension 33 connected to a rocking lever 34 by means of a pin 35 on the latter fitted within an elongated opening 36 in the extension; the rocking bar 34 is mounted by means of a pin 37 in an adjustable bifurcated support 38 on a frame 39 secured to the base 10 by locking nuts 40. This rocking bar 34 is the means by which movement is transmitted from the clutch to the operative parts of the parcel post machine (not shown).

To return trip lever 21 and key 13 to normal position and coincidentally to return the trip 23 into the path of the contact point 41 on the latch 24, so that it may disconnect the clutch at a positive predetermined point in its revolution, I have provided means comprising a shaft 42 running the full length of all of the keys 13 so that all 25 of the keys may be operated upon at the time that any one key has been depressed and the clutch operated. This shaft 42 is mounted in a series of bell crank levers 43, one being provided for each of the clutches, and all rockably mounted upon a shaft 44 mounted at both ends in the frame 11.

The opposite arm of the bell crank lever 43 is provided with a continuous shaft 45 which is engaged by the bifurcated end 46 of a rocking lever 47 rockably mounted on a shaft 48 to actuate simultaneously all of the bell crank levers 43 and thereby the trips 21. The rocking lever 47 is provided with an extension at its lower end constituting a cam slide 49, which rides upon a peripheral cam face 50 upon the cam 28.

The rotation of the cam member 28 operates to raise the cam slide 49, thereby moving the parts connected to it. This variation in position is best illustrated by the comparison of Figs. 2, 45 3, and 4, wherein Fig. 4 shows the cam 28 rotated approximately one-half of its rotation, thereby forcing cam slide 49 to ride upon the outer peripheral face 50 of the cam; in this position it has actuated the bell crank 43 to the limit 50 of its movement, whereby the shaft 42 has contacted the trip lever 21, raising the end of the trip connected to the key bars 20, thus raising the keys and lowering the trip 23 into position to contact the contact point 41 of the latch 24, 55 thereby removing the tooth 27 out of contact with the ratchet wheel 19; thus the clutch is disconnected and the several rotatable members comprising the driven section of the clutch are stopped in their movement at a predetermined 60 point.

The complete rotation of the cam member 28 brings that part of the peripheral face of the cam containing the dwell opposite the cam slide 49, thus allowing it to return into the dwell, and thereby removing the shaft 42 from contact with the trip lever 21 (see Fig. 2) and allowing room for the necessary movement of the trip lever 21 upon actuation of a key before the trip lever 21 will contact the shaft 42.

70 The trip lever 21 is tensioned by a spring 51 secured to a part of a keyboard plate 52, thereby retaining the trip lever 21 in engaged position with the latch 24 after the removal of the shaft 42. The cam slide 49 is tensioned against the 75 face of the cam 28 by means of a spring 53.

In the operation of the keyboard clutch one of the keys 13, which constitutes a clutch trip lever, is depressed, and, by means of the connected trip lever 21, the trip 23 is removed from the contact point 41, thereby allowing latch 24, under tension of the spring 25, to engage its tooth 27 with one of the teeth of the ratchet wheel 19; the clutch being thus engaged instantly picks up the other members constituting the driven parts of the clutch and rotates them one complete revolution; within the interval of time occupied by the rotation of the shaft 16 one revolution, the cam 28 has, by means of the cam slide 49 and its connected parts, returned the trip 23 into the path of the contact point 41 and the resulting engagement of trip 23 with latch 24 has, upon the completion of one revolution of the shaft 16, removed the tooth 27 from contact with one of the teeth of the ratchet wheel 19, thereby removing the driven elements of the clutch from contact with the drive element (shaft 16 and its attached ratchet wheel 19). The one revolution of the cam member 28, which is the main driven member of the clutch, has effected one revolution of the eccentric 32, thereby driving the cam ring 31 and its extension 33 to operate rocking lever 34, thereby transmitting rotary movement from the drive shaft 16 to vertical reciprocating movement of the rocking lever 34.

This form of clutch provides a simple and efficient means for operating an automatic keyboard wherein it is only required that an operator lightly depress one of the keys sufficiently to release the trip 23 from the contacting point 41; the power drive shaft 16 thereupon assumes the load of the operation of the various parts of the parcel post machine which may be actuated by means of the rocking lever 34. The speed of the drive shaft 16 and, therefore, the speed of the movement of the rocking lever 34, may be varied according to the operations to be performed within the parcel post machine by the lever 34. I have provided by means of this clutch a simple and efficient method of transmitting power with a minimum of friction and complication, and with the most efficient operation in the smallest interval of time. 30 35 40 45

The structure of the clutch itself and the means for controlling and actuating the movement thereof, together with the other objects set forth, 50 may be varied in form without departing from my invention as herewith claimed, the showing of this description and drawing being merely an illustration of one embodiment of my invention.

Illustration of the embodiment of my invention. 55
While the form of mechanism here shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow. 60

I claim:

1. A clutch device comprising a cam, a latch pivotally mounted on said cam, a ratchet wheel, a trip member normally engaging said latch to hold said latch out of engagement with said ratchet wheel, means for releasing said trip member to permit engagement of said latch with said ratchet wheel to cause movement of said cam, and restoring means engaged by said cam and movable by rotation of said cam into engagement with said trip member to move said trip member into the path of rotation of said ratchet wheel.

latch to engage said latch and release said latch from said ratchet wheel.

2. A clutch device comprising a driving member, a driven cam member, a latch pivotally carried by said cam on one side thereof and normally tending to engage said driving member to cause rotation of said cam member therewith, a trip member positioned on the same side of said cam and normally directly engaging and holding said latch out of engagement with said driving member, means for releasing said trip member and clutch-disengaging means comprising a movable member in engagement with said cam and a member operatively connected thereto and adapted to engage said trip member and project said trip member into position to engage said latch during rotation of said cam to release said latch from engagement with said driving member.

3. In a device of the character described, a drive shaft, a ratchet wheel fixed to said shaft,

a cam wheel loosely mounted on said shaft and having a cam face, a latch pivotally secured on one side of said cam wheel, a trip member positioned on the same side of said cam, said latch having a tooth adapted to engage said ratchet wheel and a projection directly engageable by said trip member, said trip member normally engaging said projection to hold said latch tooth out of engagement with said ratchet wheel, means for releasing said trip member from said projection, and restoring means adapted to engage said trip member, said restoring means engaging the cam face of said cam wheel and actuated thereby, said restoring means, during rotation of said cam wheel through engagement of said latch tooth and said ratchet wheel, engaging said trip member and projecting said trip member into position to engage said latch projection to release said latch tooth from said ratchet wheel.
